PRINTING TELEGRAPH APPARATUS

Charles W. Bureky, Chicago, Ill., assignor to Teletype Corporation, Chicago, Ill., a corporation of Delaware

Application December 19, 1938, Serial No. 246,548

16 Claims. (Cl. 178—25)

The present invention relates to printing telegraph apparatus and more particularly to such apparatus capable of tabulation recording.

The principal object of the invention is to provide in a telegraph printer an efficient and smoothly operating tabulating mechanism having means for assuring consistent operation despite a limited degree of maladjustment.

Another object of the invention is to provide means for assuring accurate operation under certain marginal conditions.

Another object of the invention is to provide means to assure formation of a blank vertical spacing between adjacent vertical typed columns in a record page.

The above and other objects of the present invention are accomplished by the provision in a printing telegraph apparatus, of the type disclosed in U. S. Patents Nos. 1,904,164 and 2,023,121 jointly, of a tabulator bar which extends across the front of the machine and is pivotally carried by brackets mounted on the frame of the machine and capable of swinging toward and away from the movable carriage. The tabulator bar carries a number of adjustable members which determine the positions at which the type carriage comes to rest after spacing during the tabulating cycle.

Spacing mechanism of the printing apparatus comprises a multi-toothed spacing ratchet or escapement wheel adapted to cooperate with a pair of pawls which are actuated by the printing bail to function as an escapement mechanism so that, upon each revolution of the printing cam shaft, a spacing worm gear, associated with the spacing ratchet, is permitted under normal operating conditions to escape one tooth at a time, and hence to rotate through a corresponding angle.

According to the aforementioned patents, function levers are provided which operate in accordance with the setting of a series of selector vanes. The present invention contemplates the provision among these function levers of a tabulating function lever which, when selected, is drawn toward the selector vanes by its spring. When this occurs, a rear extension of the function lever rises and lifts a rearwardly extending arm of a horizontal lever member, which is pivotally mounted beneath the function lever and has rearwardly and forwardly extending lever arms, the latter normally latching the tabulator bar against operation by its spring. When the rear end of this horizontal lever is raised, it lifts, through suitable linkage, the

upper spacing pawl out of engagement with a tooth of the spacing ratchet, at which time the front end of said horizontal lever member is lowered, thereby unlatching the tabulating bar to permit the latter to be moved by its spring toward the type carriage. While the upper spacing pawl is thus disengaged from the ratchet, the lower spacing pawl remains in its normal position entirely free of the teeth on the ratchet, thus permitting the spacing worm gear to rotate continuously, and therefore the carriage will be moved continuously.

To bring the carriage to rest after tabulating, the upper space pawl is permitted to drop into engagement again with the ratchet. This latter function is effected by the cooperation of a carriage borne cam element with one of the adjustable members borne by the tabulator bar. This cam forces or cams the tabulator bar forward or away from the carriage, against spring tension, and in so doing disengages the horizontal lever member to be restored to its normal position into normal latching engagement with the tabulator bar. This restoring movement of the horizontal lever member permits the upper spacing pawl to fall into engagement again with a tooth on the spacing ratchet, which brings the carriage to rest.

Should the tabulator signal be received when the carriage is immediately to the left of a tabulator stop position, a marginal condition is encountered wherein this invention provides against irregular operation which might result from maladjustment of certain springs or of the friction clutch of the spacing mechanism. The invention provides a latch or blocking member on the control arm of the tabulator bar which operates to prevent an undesired restoration of a tripped tabulator bar.

A better understanding of the invention may be had from the following description, taken in conjunction with the accompanying drawings wherein,

Fig. 1 is a front elevational view of the principal part of the printing apparatus showing the application thereto of the tabulating mechanism embodying the present invention supplemented with a schematic circuit diagram showing a transmitter and a plurality of receivers in the same line circuit;

Fig. 2 is a transverse cross-sectional view of the printing apparatus taken approximately along line 2—2 of Fig. 1;

Fig. 3 is a sectional view taken on line 3—3 of Fig. 2;

Fig. 4 is a detail rear elevation of the spacing mechanism of the printing apparatus described by the aforementioned patents;

Fig. 5 is a sectional plan view taken on line 5—5 of Fig. 1; and

Figs. 6 to 14 inclusive, are views showing the various operative positions of the mechanism of the present invention.

In the accompanying drawings, like reference characters indicate like parts throughout the several views. For a complete understanding of details not disclosed herein, and which form no part of the present invention, reference may be had to U. S. Patents Nos. 1,904,164 and 2,023,121.

As disclosed in Fig. 1, a transmitter 1 is shown diagrammatically as connected in a signal line 3, in which are also connected, line magnets 4 and 5 of receiving printers 6 and 7, respectively (also shown diagrammatically), and line magnet 11 of the printing telegraph apparatus, indicated generally as 9. The transmission of signals is effected, as is well known, either through a keyboard controlled or a tape controlled sending device which operates the sending contacts 8 permutably to transmit permutation code signals over the signal line 3. It is understood, of course, that the printers 6, 7, and 9 are of identical construction, although only the printer 9 will be described in detail.

Briefly, having reference to Figs. 1 to 4, inclusive, the printing apparatus to which the tabulating mechanism of the present invention is applied comprises a typing machine (shown generally as 9 in Figs. 1 and 2) which includes a primary selecting mechanism, indicated generally by the receiving electromagnet 11 (Fig. 1), which is of the sword-and-T type disclosed in U. S. Patent No. 1,745,633 (also fully disclosed in Patent No. 1,904,164), and a secondary selector or selector vane assembly, indicated generally as 12. The selector vane assembly 12 controls through a series of bell cranks 13 (Fig. 1), a corresponding series of curved code bars 14 carried in a movable type carriage. As set forth in Patent No. 1,904,164, this type carriage, indicated generally as 15, is movable longitudinally with respect to a stationary platen (not shown).

Referring particularly to Fig. 2, a motor (not shown) supplies power to a main operating shaft 21 which carries the spacing mechanism, indicated generally as 22 (Figs. 2 and 4). The spacing mechanism 22, which will be described more in detail hereinafter, controls, through a gear 28, shaft 29, gear 31, and rack 32 (Fig. 2), the movement of type carriage 15 to form character spaces, effecting also in this movement a winding of a carriage return spring mechanism, indicated generally as 33.

Upon receipt of the carriage return signal, a function bar 34 is tripped in the manner described in Patent No. 1,904,164, so as to permit spring 35 to rotate lever 36 against stop 37 to raise, through bell crank 38, a member 39 of a grab clutch 41. Carriage return mechanism 33 is thereupon permitted, due to the energy stored up therein, to return the carriage 15 to its normal or beginning-of-line position.

Positioned in operative relation with and parallel to the main operating shaft 21 is an auxiliary shaft 42 on which are carried various mechanisms; for example, printing bail 43, function lever bail 40, and the escapement pawls for the spacing mechanism 22. The printing bail 43, which is actuated by a printing spring 30 in proper timed relation in the operative cycle, func-

tions to reciprocate a pull bar operating member 44 to cause the operation of a type bar, as clearly described in Patent No. 1,904,164.

The selector vanes, as set forth in Patent No. 1,904,164, control a series of function levers, 5 among which is function lever 45 which is provided especially for accomplishing the objects of the present invention, and which, like the other function levers described in said patent, is pivoted on a common pivot rod 46 and is assembled in a slot in the function lever comb 47. This function lever 45, like the rest of the function levers of the series, is provided with an individual spring 43, tensioned between it and the printer frame, which tends to rotate the function lever about pivot 46 but, as clearly set forth in Patent No. 1,904,164, is restrained by the function lever bail 40, acting through rod 50 on arm 68.

Before describing further the function of lever 45, a detailed description of the spacing mechanism will be given. Having reference to Figs. 2 and 4, there is shown mounted on the main shaft 21 and located substantially centrally of the apparatus a sleeve member 51, which comprises escapement ratchet 52 and spacing worm 53. Sleeve member 51 is operably connected to the hub of a disc 54 by means of interengaging tongue and groove members 55. A collar 56 is pinned to main shaft 21 and is rotatable therewith. Interposed between disc 54 and collar 56 is disc 57 of frictional material; for example, felt. By means of a helical compression spring 58, sleeve 51 is frictionally connected to shaft 21 through the friction clutch comprising members 54, 55, and 57. Sleeve 51 is thereby rotatable with main shaft 21 unless arrested by the escapement pawls of the spacing mechanism 22, as will presently appear.

Referring to Fig. 2, it will be noted that ratchet 40 52 is provided in the present instance, with three teeth or notches 61, 61a, and 61b, the escapement of which will allow the type carriage 15 to be moved forward one step or character space for each actuation of the printing bail 43. As indicated, the escapement mechanism comprises a pair of pawls or levers 62 and 63 (pivotally mounted on bail shaft 42), and lever 64 adjustably fixed to printing bail 43. Spring 65 normally tends to bias levers 62 and 63 toward each other, since it is attached to both levers. Lever 62 is normally urged by spring 65 in a counter-clockwise direction so that laterally disposed end 66 engages tooth 61 of ratchet 52, thus forming a spacing pawl hereinafter called "upper spacing pawl" to arrest rotation of said ratchet. Lever 63 is normally held out of engagement with ratchet 52, against the tension of spring 65, by the action of lever 64 against laterally disposed end 67. Lever 64 is pivotally connected to printing bail 43 at 68 and is provided at 69 with a slot and screw adjusting means, whereby the correct relative position of escapement levers 62 and 63 with respect to ratchet 52 may be maintained.

The spacing operation from character to character in a word occurs immediately following or subsequent to the printing of a character in the following manner: Upon the printing of a character, the printing bail 43 oscillates and, in so doing, controls the operation of lever arm 70 74. During the initial portion of the clockwise movement of arm 64, lever end 67 of lever 63 follows lever 64 and lever 63, under the action of spring 65, rotates clockwise to bring the laterally disposed end 72, hereinafter called "for-

ward spacing pawl," into the path of tooth 61a. It is noted that, due to the space indicated at 70 between arm 64 and laterally disposed end 71 of lever 62, the latter lever has not been acted 5 upon, and spacing pawl 66 remains instantly in engagement with the tooth 61. However, upon the further clockwise movement of lever 64, similar movement is imparted, through laterally disposed end 71 to lever 62, thus effecting the disengagement of pawl 66 from tooth 61, and permitting ratchet 52 to rotate slightly in a clockwise direction under the influence of friction clutch members 54 to 57 (Fig. 4), until arrested by the engagement of tooth 61a with forward 10 spacing pawl 72. Ratchet 52 is thus restrained by lever 63 from rotation until the completion of the printing of a character, at which time printing bail 43 and associated lever 64 are caused to rotate counterclockwise by the action of a printing cam (not shown). Restraint of lever 62 by lever 64 through end 71 is thereby removed, permitting lever 62 to rotate in a counterclockwise direction under the influence of spring 65 into the path of tooth 61b of ratchet 52. During 15 this counterclockwise movement of lever 64, and after the aforementioned release of lever 62, lever 63 is caused to rotate in a like direction due to the action of lever 64 on end 67 thereof, thereby disengaging pawl 72 from tooth 61a and allowing ratchet 52 to resume its rotation until arrested by the engagement of pawl 66 with tooth 61b. Thus, it is observed that with the escapement mechanism just described, there is, following printing of a character, a period of 20 overlap wherein pawls 66 and 72, due to the space indicated at 70, are in effective positions concurrently to control the escapement of ratchet 52, the pawls 66 and 72 being alternately engageable with the ratchet teeth to permit the 25 escapement of ratchet 52.

It is obvious that, since worm 53 and ratchet 52 are integrally connected to sleeve 51, said worm 53 will have normally the same intermittent or step-by-step motion as was hereinbefore seen to be imparted to ratchet 62. Worm 53 is 30 meshed with worm gear 28 (Fig. 2) which is loosely mounted on vertical shaft 29, and is operably connected thereto by means of jaw clutch 41. Worm 53 and gear 28 are so related, according to the present embodiment, that one-third revolution of worm 53 will rotate gear 28 through a distance which, through gear 31 and rack 32, causes the type carriage to be advanced one character space.

From the foregoing, it will be observed that character spacing occurs automatically with the printing of each character; that is, the spacing function is merged into the printing operation. It is well known that there is a code combination allotted to each type bar; but it is possible, however, to employ a code combination, commonly known as the spacing signal, which is identified with no type bar, but which will nevertheless initiate the printing operation. Therefore, the spacing between words is accomplished in exactly the same manner as set forth when a spacing signal is received, except that no type bar is operated and consequently no character is printed.

Upon receipt and execution of code signal for functional operations, such as shift and bell, it is desirable to execute the signal without affecting spacing. In execution of such signals, spacing is suppressed by limiting movement of 55 printing bail 43 and arm 64 to a fractional move-

ment such that the movement of the forward pawl 72 does not permit the pawl to enter the path of teeth of ratchet 52, and the upper pawl 66 does not disengage from the tooth 61.

In accordance with the present invention, continuous spacing may be effected upon receipt of a code combination signal known as the tabulating code signal which functions to initiate operation of the tabulating mechanism. In execution of this signal, spacing is suppressed. The mechanically operated tabulating arrangement of the present invention comprises a tabulator bar 81 extending across and in front of the printing machine, as shown in Fig. 1. Bar 81 is provided with depending portions 82 and 83 through 15 which it is pivotally mounted on bracket 84 carried on the printer frame. Thus, tabulator bar 81 is adapted to be swingable toward and away from the carriage 15. Bar 81 is provided with a longitudinal slot 85 extending substantially the 20 entire length of the bar. In this slot are carried a plurality of adjustably positionable stop members 86 which are adapted to be clamped to the bar 81 by means of screws 87 and clamps 88 individual to each stop member (Fig. 2). As 25 indicated in Fig. 5, these stop members 86 are each provided with an inclined or cam portion 89, specially conformed so as to provide quick action upon cooperation with a cam striker 111 carried by the type carriage 15 to terminate suddenly the tabulating operation.

Tabulator bar 81 is also provided, intermediate the depending portions 82 and 83 (Fig. 1) and suitably positioned relative to function lever 45, with another depending portion 91. Attached to and depending from portion 91 is a control arm 92, the lower end of which is provided with an aperture 93 having its upper left-hand corner (as viewed in Figs. 2, 8, and 10) conformed so as to provide a reentrant stepped 40 portion or edge 94. The tabulator bar 81, as indicated in Fig. 1, normally tends to move toward the printing apparatus due to the action of a spring 95.

Cooperating with the stepped portion 94 (Fig. 45 2) is one arm 96 of a lever 97 pivotally carried at 98 on a support 99 secured to the function lever comb 47. The extremity of arm 96 is provided with a laterally disposed arm end portion 101 (Fig. 3) which cooperates with edge 94 of member 92. At the end of arm 102 of lever 97 is pivotally carried a vertically extending member 103, the upper end of which is provided (in the present embodiment) with an open ended slot adapted to engage a pin 104 carried by escapement 55 lever 62.

Function lever 45 is provided with a horizontal portion 105 so conformed that its extremity 106 engages the lower edge of arm 102 of lever 97 in such manner that, when function lever 45 is 60 permitted to rotate in a clockwise direction under the action of its spring 48 upon the proper setting of the vanes 107 in response to the tabulation code signal, the end 106 thereof is elevated, causing lever 97 to rotate slightly in a clockwise 65 direction against the tension of its spring 108. The arm end 101 of arm 96 is thus moved downwardly clear of portion 94, thus permitting spring 95 to urge the tabulator bar 81 inwardly (toward the left as viewed in Fig. 2) until wall 109 of member 92 engages arm end 101. The series of adjustable stops 86 are thus moved inwardly into the path of a cam striker 111 (Figs. 2 and 5) pivoted at 112 on a portion 113 integrally formed on a bar 115 which is comparable to bar 53 shown in 75

Fig. 1 of Patent No. 1,904,164, employed for retaining the bell crank levers 13 in operable relation to vanes 107. Thus, cam striker 111, like bar 115 and bell cranks 13, is movable with the type carriage 15 for character spacing. As viewed in Fig. 5, cam 111 normally tends to rotate in a clockwise direction about pivot 112 due to the action of spring 116, but clockwise rotation is limited by engagement of a stop pin 117, carried thereon, with the end of bar 115. Thus, upon the rightward movement of type carriage 15, cam striker 111, due to its non-rotatability in a clockwise direction, will, by its camming action on stop members 86, actuate tabulator bar 81 outwardly, but upon the leftward movement of type carriage 15, cam striker 111, upon striking the series of stop members 86, will be rotated counterclockwise against the action of spring 116 sufficiently to pass the cam portions 89.

Upon the clockwise rotation of lever 97 due to the selection of function lever 45, arm 102, and consequently link 103 carried thereon, will be raised and in so doing will, through pin 104, lift upper spacing pawl 66 out of engagement with the tooth of the ratchet 52 which (since pawl 72 is prevented from engaging any tooth of the ratchet 52 due to fractional movement of lever 64) permits the worm gear 53 to rotate continuously with the main shaft 21, and therefore the carriage will be spaced continuously so long as the spacing pawl 66 is held out of operative engagement with ratchet 52, which pawl will be maintained in this position due to the engagement of arm end 101 with the under side of stepped portion 94. Thus, carriage 15 will be moved continuously until cam striker 111 engages one of the series of stops 86, when cam striker 111 will urge, through stop cam 89, tabulator bar 81 outwardly and portion 94 inwardly (as viewed in Fig. 2), the effect of which is to disengage portion 94 from arm end 101, whereupon lever 97 will be rotated in a counterclockwise direction by its spring 108 into the position shown in Fig. 2, in which event portion 103, carried on arm 102 of lever 97, will be lowered, permitting pawl 66, under action of spring 65, to engage one of the teeth 61, 61a, or 61b of the ratchet 52.

The function lever 45 will have been returned to its non-selective position, as shown in Fig. 2, 50 because of the fact that during the cycle pursuant to the reception of the tabulating signal, the function bail 40 will have been reciprocated through a complete cycle although to but a fractional or space-suppression distance and return 55 so that rod 50 and, therefore, member 47 are again in normal position shown.

In review, during a normal tabulation operation, the consecutive relative positions of arm end 60 101 and edge 94 are as follows: Normally, as shown in Fig. 2, arm end 101 is up, control arm 92 is urged counterclockwise by its spring 95 (Fig. 1) and is restrained by engagement of stepped portion 94 with arm end 101. Arm end 65 101 moves downward to disengage itself from stepped portion 94 and control arm 92 is moved by its spring 95 until edge of aperture 93 engages arm end 101, as shown in Fig. 8. Arm end 101 moves upward and engages edge 94, as shown in Fig. 12. Control arm 92 by action of cam striker 70 111 then rotates clockwise and edge 94 disengages from arm end 101, which rises under power from its spring 108, and control arm 92, upon being released from control of cam striker 111, rotates counterclockwise until edge 94 engages arm end 75

101, thus attaining the normal condition shown in Fig. 2.

In a printed page formed with vertical tabulated columns, it is desirable to provide means for forming vertical unprinted lines or gutters between adjacent printed columns of typed record. To attain this effect, provision is made, in a structure according to prior art, that a tabulation spacing step shall be not less than three word spaces. Operators of such machines are instructed accordingly, but to assure the attainment of this effect, means is provided in the structure according to the present invention which becomes effective in case the operator neglects the instruction.

In the normal tabulation cycle traversed immediately above herein, with striker 111 midway between cams 86 and 86A, as shown in Fig. 5, member 101 moves downward from its position shown in Figs. 2 or 6 to its position shown in Fig. 8, as 20 function lever 45 rotates clockwise whereupon, as member 101 clears the corner of edge 94, the control arm 92 and tabulator bar 81 are released for movement from the position shown in Fig. 6 to the position shown in Fig. 8. Then, when function 25 lever 45 starts to rotate counterclockwise in returning, member 101 follows until edge of 94 is engaged. The continuous spacing movement of the carriage 15 has been begun early in the movement of member 101, and striker 111 engages 30 cam 86A, rocking the bar 81 and arm 92 clockwise, thereby disengaging end 101 from the corner of edge or step 94, whereupon end 101 rises, lever 97 rocks counterclockwise, member 103 descends, pawl 66 is engaged by tooth 61, and carriage 15 stops.

Should the keyboard operator either directly or through tape control transmit a tabulation signal in error when the striker 111, Fig. 5, is but one or two character spaces to the left of the tabulation stop position, the steps of operation will be as follows: From normal position shown in Figs. 2 or 6, arm end 101 descends to its position shown in Fig. 8, the carriage 15 starts by a fully tensioned quickly acting clutch, arm 92 moves to 45 its position shown in Fig. 8 due to the fact that striker 111 first acts through cam 86A and rocks arm 92 from its spring controlled position shown in Fig. 8 to its cam controlled position shown in Fig. 10; then striker 111 passes cam 86A and releases arm 92 to return to its spring controlled position shown in Fig. 8, after which the lateral portion or end 101, now rising in its function of following the returning movement of member 45, engages edge 94 as shown in Fig. 12. Thus, end 55 101 does not return to the position shown in Figs. 2 or 6, and carriage 15 continues in tabulating motion until striker 111 engages cam 86B (Fig. 5) to rock arm 92 from its position shown in Fig. 12, to its position shown in Fig. 10, after which 60 all parts return to positions shown in Figs. 2 or 6, and carriage 15 stops in tabulation position 86B instead of position 86A. By observation of a home recorder, the operator is advised of his error.

Slippage is inherent in a friction clutch, and 65 to nullify slippage in the clutch, the present invention provides a latch 121 which is pivotally carried at 122 on arm 92 and is spring urged in a clockwise direction (as viewed in Figs. 6, 8, 10, and 12) by a spring 123 distended between a 70 spring post 120 on arm 92 (Fig. 3) and a stop pin 124. Stop pin 124 is carried on the latch 121 and bears against the outer edge of arm 92 when the arm end 101 is in the position shown in Fig. 8. Having reference to Figs. 6 to 12, inclusive, 75

in Figs. 6 and 7 is shown the normal relative position of the tabulator bar 81 and cam striker 111 carried on the carriage 15 wherein said cam striker 111 is immediately to the left (as would be viewed in Fig. 1) of the stop element 86. In Figs. 8 and 9 is shown the same relative position of the tabulator bar 81 and cam element 111, but with the tabulator bar 97 in its tripped or clockwise position with the arm end 101 out of latching engagement with the edge 94. Carriage 15 with its cam striker 111 will then move in the direction of the arrow 124 (Fig. 9). In so moving, the striker 111 will urge the stop element 86 outwardly (as viewed in Fig. 11) to cause the tabulator bar 81 and the arm 92 integral therewith to assume the position shown in Fig. 10, wherein the arm 92 has been rocked to its clockwise position. In this position, the lever 97 has not yet started its upward or counterclockwise movement, thus a clearance obtains between the latch 121 and lever 97. In Fig. 14 is shown a transit position wherein arm 92 has begun its counterclockwise movement under influence of spring 95, and lever 97 has risen into contact with latch 121. Under these conditions (as noted in Figs. 10 and 14) lever 97, through its laterally disposed portion 101, is blocked against upward movement by the latch 121.

In Figs. 12 and 13 is shown the condition of the tabulating control mechanism when the striker 111 has just passed over and beyond the stop element 86A. In this position the tabulator bar 81 and arm 92 have been returned to their counterclockwise position by the spring 95 (shown in Fig. 1). In this condition of the apparatus, the arm end 101 engages the stepped edge 94, and is now in a position (due to the stepped relationship between portion 94 and the tip of latch 121) to engage the latch 121.

In the operation described above, when carriage 115 passed stop element 86A without stopping, the arm end 101 did not engage the latch 121 in the manner shown in Fig. 12 until after striker 111 had engaged the stop element 86B. Should slippage of the clutch cause a slow start of carriage 115, the operation of arm 92 by striker 111 will be delayed, and arm end 101 in rising may engage the latch 121, producing a sequence of operations as follows: From normal (Fig. 6), arm end 101 descends (Fig. 8), arm 92 moves fully to its clockwise position then starts rightwardly, and arm end 101 starts up (Fig. 14). From a quick clutch start, latch 121 will clear from the path of end 101, and end 101 will engage the left vertical edge 109 of 93 and then the horizontal edge of step 94, but from a slow clutch start, latch 121 will not have cleared from the path of end 101, and end 101 will engage the lower edge of latch 121 being thus latched down and prevented from rising above the level of the horizontal edge of step 94, after which, further movement of latch 121 drops latch 121 away from end 101, and end 101 rises and engages the horizontal edge of step 94 after striker 111 has passed cam 86A. Obviously, were the latch 121 omitted from the structure in Fig. 14, the arm end 101 would have risen to engage the vertical edge of step 94 after a slow clutch start without having engaged the horizontal edge of step 94, and the stoppage of carriage 115 would have occurred at cam 86A, but operation of latch 121 assures that arm end 101 will engage the horizontal edge of step 94, thus attaining uniform operation despite any maladjustment of the friction clutch.

It is seen from the foregoing that an arrange-

ment has been provided for insuring consistent and uniform operation of the tabulating mechanisms of a series of printers connected in the same line circuit. It is, of course, understood that this application is intended to cover not only the specific embodiment disclosed, but also such changes or modifications as come within the spirit of the invention or scope of the following claims.

What is claimed is:

1. In a recorder, elements movable normally one character space, means comprising an instrumentality operated selectively in response to a predetermined code signal for causing said elements to advance through a plurality of spaces at a time from one recording position to another, and means effective invariably to block the return movement of said instrumentality directly from its operated position to its normal position. 15

2. In a recorder, means to effect recording operations, means to limit the movement of said means to a single character space at a time, means comprising an instrumentality operated selectively in response to a predetermined code signal to render said second recited means ineffective to limit the movement of said first recited means to single spaces, and means effective invariably to block the return movement of said instrumentality directly from its operated position to its normal position. 20

3. In a recorder, recording elements, means operable normally to move said recording elements one character space upon each recording operation, means comprising an instrumentality operated selectively in response to a predetermined code signal for causing said recording elements to advance through a plurality of spaces at a time from one recording position to another, and lockout means effective invariably to block the return movement of said instrumentality directly from its operated position to its normal position. 30

35

3. In a recorder, recording elements, means operable normally to move said recording elements one character space upon each recording operation, means comprising an instrumentality operated selectively in response to a predetermined code signal for causing said recording elements to advance through a plurality of spaces at a time from one recording position to another, and lockout means effective invariably to block the return movement of said instrumentality directly from its operated position to its normal position. 40

4. In a recorder, a traveling carriage, recording mechanism cooperating therewith, means for effecting the normal spacing movement of said carriage, other means comprising an instrumentality operated selectively in response to a predetermined code signal for effecting the continuous movement of said carriage through variable sequences of character spaces, and further means effective invariably to block the return movement of said instrumentality directly from its operated position to its normal position. 45

5. In a telegraph system, a line circuit extending between a plurality of stations, a transmitter at one of said stations, a printing telegraph receiver at each of the other stations including a tabulating mechanism, means in each printer comprising an instrumentality operated selectively in response to a predetermined control signal from said transmitter for operating said tabulating mechanism, and means in each printer effective invariably to block the return movement of said instrumentality directly from its operated position to its normal position. 55

6. In a telegraph system, a line circuit extending between a plurality of stations, a transmitter at one of said stations, a printing telegraph receiver at each of the other stations, a movable carriage in each receiver, means in each receiver operable normally under the control of said transmitter to move the carriage one character space upon each recording operation, means in each receiver comprising an instrumentality operated selectively in response to a predetermined 70

75

- code signal for causing the carriage to advance through a plurality of spaces at a time from one recording position to another, and lockout means in each receiver effective invariably to block the 5 return movement of said instrumentality directly from its operated position to its normal position.
7. In a recorder, selector mechanism responsive to received code combinations of signaling impulses, a type carriage movable normally one 10 character space for each recording operation, means comprising an instrumentality operated under the control of said selector mechanism for causing said carriage to advance uninterruptedly through a plurality of spaces at a time from one 15 recording position to another, and means effective invariably to block the return movement of said instrumentality directly from its operated position to its normal position.
8. In a telegraph recorder, selector mechanism 20 comprising a plurality of function levers responsive to code signals, a type carriage, spacing mechanism operative normally to control the advancement of said type carriage one character space at a time, tabulating mechanism comprising 25 an instrumentality operated under control of one of said function levers to control the uninterrupted advancement of said type carriage through a plurality of spaces at a time, and means effective invariably to block the return movement of said instrumentality directly from its operated 30 position to its normal position.
9. In a recorder, selector mechanism responsive to received code combinations of signaling impulses, a type carriage movable normally one 35 character space for each recording operation, means comprising an instrumentality operated under the control of said selector mechanism for causing said carriage to advance uninterruptedly through a plurality of spaces at a time from one 40 recording position to another, and lockout means effective invariably to block the return movement of said instrumentality directly from its operated position to its normal position.
10. In a telegraph recorder, selector mechanism 45 responsive to code signals, a carriage, spacing mechanism operative normally to control the advancement of said carriage one character space at a time, said mechanism embodying an escape- 50 ment device including a pair of pawls and means to bias said pawls attrahently, tabulating mechanism comprising an instrumentality operated under the control of said selector mechanism to disable one of said pair of pawls to control the 55 advancement of said carriage through a plurality of spaces at a time, and lockout means effective invariably to block the return movement of said instrumentality directly from its operated position to its normal position.
11. In a telegraph recorder, a spacing mechanism, driving means for driving said mechanism continuously, means comprising an instrumentality operated selectively in response to a predetermined code signal for starting said driving means, said instrumentality having drive maintaining and drive stopping positions, and a latch 60 effective invariably to block the movement of said instrumentality directly from its drive maintaining position to its drive stopping position.
12. In a telegraph recorder, a spacing mechanism, signal responsive means for starting said spacing mechanism, a three-condition control member engaging said spacing mechanism for stopping said spacing mechanism, and means preventing at all times direct transition of said member from its first condition to its third condition while facilitating transition of said member from its first condition to its second condition and from its second condition to its third condition. 5
13. In a telegraph recorder, a spacing mechanism, control means comprising an instrumentality operated selectively in response to a predetermined code signal for operating said spacing mechanism continuously, holding means to hold said instrumentality in predetermined spacing mechanism operating position, and a latch effective invariably to assure said predetermined cooperation between said holding means and said instrumentality. 10
14. In a telegraph recorder, a spacing mechanism, control means comprising an instrumentality operated selectively in response to a predetermined code signal for operating said spacing mechanism continuously, holding means to hold said instrumentality in predetermined spacing mechanism operating position, said holding means having a shouldered portion, and a blocking element having a surface arranged in stepped relation with said shouldered portion to assure invariably said predetermined cooperation between said holding means and said instrumentality. 15
15. In a recorder, elements movable normally one character space, means comprising an instrumentality operated selectively in response to a predetermined code signal for causing said elements to advance through a plurality of spaces at a time from one recording position to another, holding means to hold said instrumentality in operated position, said holding means having a shouldered portion, and a blocking element having a surface arranged in stepped relation with said shouldered portion to assure invariably a predetermined cooperation between said holding means and said instrumentality. 20
16. In a recorder, elements movable normally one character space, means comprising an instrumentality operated selectively in response to a predetermined code signal for operating said spacing mechanism continuously, holding means to hold said instrumentality in predetermined spacing mechanism operating position, said holding means having a shouldered portion, and a blocking element having a surface arranged in stepped relation with said shouldered portion to assure invariably said predetermined cooperation between said holding means and said instrumentality. 25
